(57) **CLAIM**

The ornamental design for a gene amplification chip for medical and laboratory use, as shown and described.

DESCRIPTION

1.1: Front view of the gene amplification chip for medical and laboratory use.

1.2 : Cross sectional view thereof, sectioned horizontally along line **1.2** in reproduction **1.1**.

1.3 : Enlarged cross-sectional view thereof, sectioned vertically along line **1.3** in reproduction **1.1**.

1.4 : Enlarged cross-sectional view thereof, sectioned vertically along line **1.4** in reproduction **1.1**.

1.5 : Perspective view thereof.

1.6 : Back view thereof.

1.7 : Top view thereof.

1.8 : Bottom view thereof.

1.9 : Right view thereof.

1.10 : Left view thereof.

The dashed broken lines depict portions of the gene amplification chip for medical and laboratory use that forms no part of the claimed design.
